UNITED STATES PATENT OFFICE.

BRITAIN HOLMES, OF BUFFALO, NEW YORK, ASSIGNOR TO HIMSELF AND
EDWARD HOLMES, OF SAME PLACE.

MODE OF INCASING KNOTS OR OTHER DEFECTS IN WOOD.

SPECIFICATION forming part of Letters Patent No. 256,567, dated April 18, 1882.

Application filed October 21, 1881. (No model.)

To all whom it may concern:

Be it known that I, BRITAIN HOLMES, a citizen of the United States, residing in Buffalo, in the county of Erie and State of New York, have invented certain new and useful Improvements in the Mode of Incasing Knots or other Defects in Wood or other Material, so as to make them water-tight, of which the following is a specification.

- 10 The object of my invention is to provide a cheap and reliable means for covering knots or other defects in boards or other material, or in staves, barrels, tanks, or other liquid-holders, so as to make them water-tight. It is
15 particularly useful in sugar-barrels and other packages where the heads or other parts are made of pine, for which clear lumber free of knots has been required heretofore; and the invention consists in forming a shallow open-
20 ing around the knot, (either with an incising-tool or with the covering-cap itself, as will be more clearly hereinafter specified,) or forming a depression around and over the face of the knot or other defect, and then inserting a cap
25 or piece of sheet metal corresponding to the shape of the opening, so as to cover the knot or defect with its edge embedded in the wood around the knot, and make a smooth surface, and also form a close water-tight joint around
30 and over the knot, as will be more clearly hereinafter shown by reference to the drawings, in which—
Figure 1 is a face view of a barrel-head, illustrating my invention. Fig. 2 is a section through line X X, Fig. 1. Fig. 3 is an enlarged section through a board, showing my invention applied thereto. Fig. 4 is an enlarged section, showing a modification of my invention. Fig. 5 is a central section through Fig.
35 9. Figs. 6, 7, and 8 are sectional views of modifications of my invention, and Fig. 9 represents a top view of one of the metal caps.

In carrying my invention into practice I first make a thin slit or depression, A, around
45 the knot or other defect a, when the metal covering-cap is not heavy enough to allow its rim to be driven directly into the wood, (see Figs. 1 and 2,) which opening is made by an ordinary hollow punch or other incising-tool,
50 when the cap itself is not heavy enough for the purpose, as above mentioned. A thin metallic cap, B, having a rim, C, surrounding it,

(see Fig. 5,) and of the same form as the opening A, (when such an opening is required,) is then placed in said opening, or on the article, 55 and forced down by a piston or a hammer, or other similar means, until the top of the cap lies on or covers the knot or other defect, and the rim is forced tightly into the wood, thereby forming a close tight joint around the knot 60 or other defect, which joint becomes tighter as the wood becomes wet and swells. It will be seen that by this arrangement the wood acts as a packing against the metal at a point in a line surrounding the knot, and more or less 65 below the surface of the wood, and that as the cap is forced down the rim wedges into the wood, and is forced tightly against the outer side of the opening all around the knot, so as to form in said line a perfectly water-tight 70 joint.

In Fig. 4 I have shown a modification in which the cap-rim C is made to flare outward, as shown in the detached sectional view of a cap, B, in said Fig. 4. E is a depression, into 75 which the said cap is forced into place with sufficient force to bring the rim into the shape of the depression, as shown.

If desired, the cap B may be closely fitted into a depression, E, as shown in Fig. 6, or a cap, F, may be formed, as shown in Figs. 7 and 8, and forced down into said depression, thereby forming a close joint around the knot, it being forced into the position shown by the dotted lines e, so as to extend the periphery of 85 the cap and tighten the joint.

In Fig. 8 I have shown a nail, f, for holding the cap in place, which device might be used in some cases.

The caps or disks B are usually made of tin-plate; but any other suitable metal or material may be used, and the rim C may be either round, oval, or of any other desired form to surround the knot or other defect.

I claim as my invention—

The combination, with a wooden strip having a knot, of a metallic piece covering the knot portion, with its edge embedded in the wooden strip around the knot, as and for the purpose set forth.

BRITAIN HOLMES.
